FIBROUS CONTAINER

Harold E. McCrery, Oakwood, Ohio, assignor to
 Plyfiber Container Corporation, Garwood, N. J.,
 a corporation of New Jersey

Application February 1, 1941, Serial No. 376,947

8 Claims. (Cl. 229—4.5)

This invention relates generally to containers formed preferably of fibrous sheet materials and particularly to such containers constructed with a plurality of plies of sheet material formed in a cylindrical or other desired shape. In its widest purview, the invention includes combinations of sheet metal and fiber board united by stitching or stapling to provide a strong and economical type of container, but the invention is more particularly directed to fiber board containers of various shapes, particularly cylindrical shapes, of either one or more plies, where the parts may be economically die-stamped and assembled under modern production methods rapidly and cheaply by means of a unique arrangement, and such fiber board containers may be made substantially air and water impervious, and while extremely light, nevertheless, may be made of strong and rigid constructions that are competitive with metal or wood barrels or like containers.

Heretofore, a variety of wood, metal or fiber board containers have been in use or have been suggested, but such containers have been commercially disadvantageous because of either one or several of the following reasons: (1) excessive weight, (2) excessive expense, (3) corrosion of the container, (4) flimsiness, (5) leakage, (6) difficulty of handling.

Therefore, it is an object of my invention to produce a fiber board container having one or more plies of sheet material in its walls in such fashion that the parts may be rapidly and easily constructed by simple die-cutting, stamping and forming operations and may be easily assembled.

It is an object of my invention to construct such a class of containers either in cylindrical or other shapes, and to preferably unite the various portions of the container by sewing or stapling operations.

It is a further object of my invention to form such containers of a plurality of sheets of fiber board or the like, and to interleave the edge portions of the plies in such fashion as to minimize the effects of overlapping parts and preferably to sew various portions of such containers together in order to obtain peculiar assembly economies and to obtain unique strength advantages where the walls are formed in a multiply construction, and also to obtain certain advantages in using the containers.

It is a further object of my invention to utilize sheet metal in combination with fiber board in such class of containers.

It is a further object of my invention to provide a unique head for such class of containers.

It is a further object of my invention to provide a rolling strip for cylindrical containers of such class, thus permitting ease in handling.

It is a further object of my invention to form such containers with a cylindrical body portion, to sew the head in place, and to produce and to friction-fit the head in such manner that the same may be depressed downwardly within the cylinder to maintain contact with the goods inside the container, even though portions of the materials originally packed have been removed from the container.

It is a further object of my invention to provide various types of liners for such containers in such fashion that raw edges of the fiber board stock will not come into contact with the goods packed within the container.

It is a further object of my invention to provide a new and improved closure structure for closing the filling openings of such containers.

It is a further object of my invention to provide sewn multiply containers of the class described, wherein a ribbon of adhesive material is inserted between interleaved marginal portions of the plies, and sewn in place in such fashion that the adhesive material tends to fill in, at least in part, the holes created by the stitching needles.

It is a further object of my invention to provide stitching means for such containers and to also unite various plies of a multiply wall to a minimum extent in their overlying areas, preferably by sewing, in order to attain maximum strength resistance to shock or impact forces, as well as to give good resistance to compressive forces.

These and various other objects and advantages will be readily understood from the following description taken in connection with the accompanying drawings of certain preferred embodiments of the invention, it being understood that the herein description and drawings are set forth for illustrative purposes only, and that modifications may be made therefrom:

In the drawings:

Fig. 1 is a perspective view, partly broken away, of a fiber board container embodying my invention;

Fig. 2 is a fragmentary cross-section taken on the line 2—2 of Fig. 1;

Fig. 3 is a fragmentary cross-section taken on the line 3—3 of Fig. 1 and illustrates the interleaving of the end portions of the plies of the wall of the container;

Fig. 4 is a fragmentary cross-section of the container illustrated in Fig. 1, after the top there-

of has been opened, the contents partially removed, and the top slid downwardly within the container, in order that the top may contact the remaining contents thereof;

Figs. 5, 6, 7, 8, 9 and 10 represent fragmentary, exploded perspective views (for purposes of clarity) of an alternate embodiment of my invention also illustrated in Fig. 12;

Fig. 11 represents a fragmentary perspective of the upper portion of the container illustrated in Fig. 12;

Fig. 12 is a cross-section taken on the line 12-12 of the container illustrated in fragmentary perspective in Fig. 11;

Fig. 13 is a fragmentary elevation, partly in cross-section, of a modified sheet metal and fiber board container illustrating an alternate embodiment of my invention;

Fig. 14 is an elevation of a container illustrating an alternate form of my invention and showing a rolling strip;

Fig. 15 is a fragmentary perspective of a modified bottom with a liner for one of my containers with slits 30 shown in a staggered relation;

Fig. 16 illustrates in fragmentary cross section, a multiply wall of material having an inner liner;

Fig. 17 is a fragmentary section of an end portion of a container made in accordance with my invention, which end portion is provided with a special stiffening ring;

Fig. 18 is a plan view of the stock from which the end portions of the containers are blanked, and shows the corners which remain, which corners may be utilized as support portions for the bottoms of the containers.

Referring to the figures, in which common parts are designated by common identifying numerals, and referring particularly to Figs. 1-4, 16 represents a container having a cylindrical body 12 and bottom and top portions 14 and 16 respectively.

As illustrated, container 16 may have three separate and distinct plies of fiber board, indicated as 18, 20 and 22, both in the cylindrical body 12 and in the bottom and top portions 14 and 16.

As best shown in Fig. 3, the overlapping ends of plies 18, 20 and 22 are interleaved in order to minimize the overlap joint, and so that top and bottom portions 12 and 14 may seat tightly within cylindrical bdy portion 12. If desired, a strip 24 of asphalt base tape, or the like, may be interposed at the overlap of plies 18, 20 and 22, which tape may be thermo-plastic in nature, so that when the top row of stitching as at 25 and 27 is stitched to unite the overlapping plies, the overlapping plies may be ironed in such fashion that the asphalt base tape tends to definitely fill in the holes caused by the stitching needles in the fiber board.

As indicated clearly in Figs. 1 and 2, the bottom portion 14 has a depending flange 26 and the top portion has an upstanding flange 28, which, it will be recognized by those skilled in the trade, may be provided by a series of radial slits indicated generally as 30, or by other means of die-cutting and scoring therein. As indicated, after the cylindrical body 12 is formed upon a forming mandrel and its plies interleaved as indicated, the plies are stitched into place as clearly indicated, preferably by top rows of stitching 32 and 34.

The top 16 of the container will be provided with an orifice 36 and after the container is filled,

a conventional expanded metal cover may be fitted therein, as indicated at 38.

The sewn seams may be dipped preferably in paraffin, as indicated generally by the numeral 40.

As a support 42 for the center of the container, a series of plies 44 of fiber board, preferably generally triangular scrap pieces 46, such as are indicated as left from a square piece of board (Fig. 18) after the top portions are blanked out therefrom, will be utilized to build up a platform, equal in thickness to the extent of depending flange 28, of bottom portion 14.

As particularly shown in Fig. 4, the stitching 32 and 34 of top portion 16 may be cut, and as the container is emptied, top portion 16 may be pressed downwardly to follow the material, because top portion 16 is friction fitted into cylindrical body 12.

Referring particularly to Figs. 5, 6, 7, 8, 9, 10, 11 and 12, the container 48 here illustrated is generally similar to that illustrated in Figs. 1-4; however, a special cover arrangement identified generally as 50 and heavy strengthening boards 52 and 54 are provided at the bottom and top of the container respectively, as indicated.

These strengthening boards may be of heavy wood, thick fiber board, or even metal, and will generally be stapled by staples 56 respectively to the bottom 14 in the top 16.

Top board 54 will ordinarily have a square hole 58 cut therein as indicated particularly in Fig. 7, and the cut-out may be used as cover member 60.

When hole 58 is cut in top end member 16, the cut-outs are saved and utilized as bottom plies 62 in cover arrangement 50, and will be preferably stapled as indicated to member 60. It will be realized that the plies 62 tightly fit into and friction fit preferably, circular opening 58 in top member 16.

40 The cover arrangement 50 may be held in place by wires 64, the ends of which indicated as 66 may be stapled through end member 16. If desired, all four corners of the square cover arrangement 50 may be so wired in place tightly, by twisting the wire 64 as indicated in 68; or alternatively, one corner of cover arrangement 50 may be stapled into place as at 70 and the top member 60 scored as indicated at 72, thus allowing the member 50, after the wires 68 have been removed,

45 to hinge upwardly and downwardly, as illustrated in 62. It will be realized that cover member 16 may have its stitching cut (or pulled if a chain stitch is utilized) and that the top member 16 may be pressed downwardly into the bottom of the container.

An important part of my invention is the radial slittings 30 in the upstanding flange 28 of top portion 16, inasmuch as this construction in multiply flanged tops, gives an excellent friction fit, and the flange 28 will ordinarily be formed to tension against the cylindrical body portion 12, giving an excellent tight fit.

As indicated, in Fig. 13, the cylindrical body portion may be formed with one inner ply 74 of fiber board (one ply or more if desired) and an outer ply of light corrugated metal 76 which inner and outer plies 74 and 76 may be sewn together by two rows of stitching 78 and 80, which stitching will, at the same time, hold the usual bottoms and tops 14 and 16 respectively of the container in place. These bottoms and tops may be similar to the bottoms and tops illustrated in Figs. 1-12 or may be metal-covered if desired. Also, a series of check blocks indicated as 82 may be utilized, if desired, to prevent the top portion 16

from sinking into the container. It will be recognized by those skilled in the art that this composite wall of light corrugated metal and fiber board prevents the stretching of the light corrugated metal. In other words, the fiber board holds the metal in place.

Fig. 14 illustrates that class of container shown in Figs. 1-12 which additionally, has sewn thereupon a rolling strip 84, which rolling strip permits the cylindrical containers to be easily rolled and easily turned when filled with heavy materials.

Fig. 15 illustrates a bottom member 14 for that type of container illustrated in Figs. 1-12 having additionally thereupon, a liner 86 of any desired material, such as, for example, Pliofilm or other filming material or resinous coating etc. which liner completely covers the center portion of 14 and the depending flange 86, also this figure illustrates a definitely preferred form of bottom or top wherein the marginal slits of the three plies of fiber board are staggered, thus preventing leaking tendencies.

Fig. 16 in fragmentary cross-section, illustrates the inner ply 18 of the cylindrical body portion 12 of that class of container illustrated in Figs. 1-12, with the addition of an inner liner 88 which completely covers the inside of the container and additionally has turn-back portion 90 so as to cover the raw edge indicated as 92, of ply 18.

Fig. 17 illustrates in fragmentary cross-section that class of container illustrated in Figs. 1-12 with the addition of a circular interior stiffening collar 94 which may be stapled as indicated at 96 both to the plies of cylindrical body 12 and to the upstanding flange 28 of top portion 16.

By the above described arrangements, a strong light container is obtained, preferably with a plurality of plies of material; various shapes may be employed, barrel-like or box-like, etc.; the stitching preferably will be of strong cotton thread in a lock stitch, although chain stitching may be utilized and of course linen or even metal stitching may be used; the cotton thread is particularly strong.

Those skilled in the art will recognize the peculiar strength advantage in uniting the plies only at the stitch lines; the individual plies "give" separately with the result that sudden impacts and shocks in restricted areas are resisted much more efficiently than if the plies were joined together in a solid body mass by adhesives or the like. My containers compare favorably with containers formed of light steel or heavy wood.

Various fibre-boards may be used, and like boards or equivalents may be substituted. Fibre-board up to $\frac{1}{8}$ " may be easily formed on a forming mandrel to give a cylindrical body; heavier boards are difficult, if not impossible, to handle speedily and efficiently.

It will be realized that simple tools and dies may be utilized to produce various sizes and shapes of containers embodying my invention.

Inasmuch as my invention may be utilized in part or in whole, and in variant forms in contrast to the illustrative embodiments above described, and with various equivalent structures, in part or in whole, reference should be had to the appended claims for a definition of my invention; the key essence of which is a cheap light strong container quickly and easily assembled by modern production methods.

I claim:

1. The method of constructing a container body composed of a plurality of superposed plies of fibrous sheet material each having bottom,

top and side edges, which consists in preforming each of the fibrous sheets into a form in which the side edges thereof are in overlapping surface to surface contacting relation, maintaining each of said sheets in said preformed condition, telescoping said preformed sheets relative to each other with their overlapped side edge portions in alignment and with the inner and outer side edges of each sheet extending in the same direction respectively as the inner and outer side edges of the next adjacent sheet, and then securing all of said preformed telescoped sheets together in surface to surface contacting relation along their overlapped aligned portions, the remainder of said preformed telescoped sheets being otherwise free of connection with each other.

2. The method of constructing a container body composed of a plurality of superposed plies of fibrous sheet material each having bottom, top and side edges, which consists in preforming each of the fibrous sheets into a form in which the side edges thereof are in overlapping surface to surface contacting relation, maintaining each of said sheets in said preformed condition, telescoping said preformed sheets relative to each other with their overlapped side edge portions in alignment and with said inner and outer side edges of each sheet extending in the same direction respectively as the inner and outer side edges of the next adjacent sheet, securing all of said preformed telescoped sheets together in surface to surface contacting relation along their overlapped aligned portions, the remainder of said preformed telescoped sheets being otherwise free of connection with each other, and then in moisture sealing said sheets along their line of connection with each other.

3. A container of the character described, including a body formed of a plurality of superposed sheets of fibrous material, each having bottom, top and side edges, the side edges of each of said sheets being disposed in overlapping surface to surface contacting relation with each other and said overlapped portions of each sheet being disposed in alignment with the overlapped portions of the others of said sheets, the overlapped portions of the inner and outer side edges of said sheets extending in the same direction, respectively, and means to connect all of the aligned overlapped portions of the sheets together in surface to surface contacting relation, the remaining portions of said sheets being otherwise free of connection with each other.

4. A container of the character described, including a body formed of a plurality of superposed sheets of fibrous material, each having bottom, top and side edges, the side edges of each of said sheets being disposed in overlapping surface to surface contacting relation with each other and said overlapped side edge portions of each sheet being disposed in alignment with the overlapped side edge portions of the other of said sheets, the overlapped portions of the inner and outer side edges of said sheets extending in the same direction, respectively, and the bottom and top edges of all of the sheets being co-extensive, means for connecting all of the aligned overlapped side edge portions of the sheets together in surface to surface contacting relation, and means for connecting said sheets together adjacent the top and bottom edges thereof, said superposed sheets being otherwise free of connection with each other.

5. A container of the character described, in-

cluding a body formed of a plurality of superposed sheets of fibrous material, each having bottom, top and side edges, the side edges of each of said sheets being disposed in overlapping surface to surface contacting relation with each other and said overlapped portions of each sheet being disposed in alignment with the overlapped portions of the other of said sheets, the overlapped portions of the inner and outer side edges of said sheets extending in the same direction, respectively, means to connect all of the aligned overlapped portions of the sheets together in surface to surface contacting relation, the remaining portions of said sheets being otherwise free of connection with each other, and a wear and strengthening member disposed about and connected to the outer face of the body intermediate the top and bottom edges of the latter.

6. A container of the character described, including a body formed of a plurality of superposed sheets of fibrous material, each having bottom, top and side edges, the side edges of each of said sheets being disposed in overlapping surface to surface contacting relation with each other and said overlapped portions of each sheet being disposed in alignment with the overlapped portions of the other of said sheets, the overlapped portions of the inner and outer side edges of said sheets extending in the same direction, respectively, and the top and bottom edges of all of the sheets being co-extensive, means for connecting all of the aligned overlapped portions of the sheets together in surface to surface contacting relation, means for connecting said sheets together adjacent the top and bottom edges thereof, said superposed sheets being otherwise free of connection with each other, and a wear and strengthening member disposed about and connected to the outer face of the body intermediate the top and bottom edges of the latter.

7. A container of the character described, including a body formed of a plurality of superposed sheets of fibrous material, each having bottom, top and side edges, the side edges of each of said sheets being disposed in overlapping surface to surface contacting relation with each other and said overlapped portions of each sheet being disposed in alignment with the overlapped portions of the other of said sheets, the overlapped portions of the inner and outer side edges of said sheets extending in the same direction, respectively, sealing means interposed between the aligned overlapped portions of adjacent sheets, and means to connect all of the aligned overlapped portions of the sheets together in surface to surface contacting relation, the remaining portions of said sheets being otherwise free of connection with each other.

8. A container of the character described, including a body formed of a plurality of superposed sheets of fibrous material, each having bottom, top and side edges, the side edges of each of said sheets being disposed in overlapping surface to surface contacting relation with each other and said overlapped side edge portions of each sheet being disposed in alignment with the overlapped side edge portions of the other of said sheets, the overlapped portions of the inner and outer side edges of said sheets extending in the same direction, respectively, sealing means interposed between the aligned overlapped side edge portions of adjacent sheets, the bottom and top edges of all of the sheets being co-extensive, means for connecting all of the aligned overlapped side edge portions of the sheets together, and means for connecting said sheets together adjacent the top and bottom edges thereof, said superposed sheets being otherwise free of connection with each other.

HAROLD E. McCRRERY.
